UNITED STATES PATENT OFFICE.

ADOLF POLLATSEK, OF BROOKLYN, NEW YORK.

LABELING-MACHINE.

1,384,711.

Specification of Letters Patent. Patented July 12, 1921.

Application filed March 4, 1920. Serial No. 363,315.

To all whom it may concern:

Be it known that I, ADOLF POLLATSEK, a citizen of the United States, residing in Brooklyn, in the county of Kings and State 5 of New York, have invented certain new and useful Improvements in Labeling-Machines, of which the following is a specification.

This invention relates to label applying machines, and has for an object to provide 10 an improved construction which is practically automatic in its operation and which will apply and press labels on cans, bottles, and the like of different shapes and sizes.

A further object of the invention is the 15 provision of a machine in which the parts will, without adjustment, take care of different sized bottles and labels applied thereto with equal pressure regardless of the size of the bottles.

Other objects of the invention are to improve generally machines of this type, to 20 reduce the number of parts thereof and simplify the operation.

Still other objects of the invention will 25 appear as the description proceeds; and while herein minute details of the invention are described, the invention is not limited to these, since many and various changes may be made without departing from the 30 scope of the invention as claimed.

In the accompanying drawing showing by way of example one of many possible 35 embodiments,

Figure 1 is an elevation of one side of the 35 machine;

Fig. 2 is an elevation of the other side;

Fig. 3 is a front elevation; and

Fig. 4 is a plan of the label magazine.

My improved label applying machine 40 comprises a base 10 (Fig. 1) on which are mounted a pair of side frames 11 each provided at its upper part with forward end bearings 13, (Fig. 3) an intermediate bracket 14 (Fig. 1), and a rear end bracket 45 15. A paste container 18 is located between the lower part of said side frames; and into it dips a paste roller 19 transverse to said frames. A distributing roller 20 (Fig. 2) rests upon said paste roller.

An upper supporting roller 22 (Fig. 1) 50 and a pair of lower supporting rollers 23 and 24 are rotatably mounted between said frames; and a paste belt 25 (Fig. 3) is disposed around said supporting rollers, over 55 said upper roller and under said lower rollers and engages over said distributing

roller 19. Sprocket wheels 28 (Fig. 2) are mounted at both ends of the supporting rollers and receive sprocket chains 29 sewed to both edges of said belt and engaging 60 around said wheels.

A drive-crank 31 is secured at one end of one of said lower rollers and provided with a handle crank 32 by means of which the machine is operated, but it is, of course, 65 understood that any suitable drive or power means may be substituted here or elsewhere for driving the machine.

Short shafts 35 (Fig. 1) project from the 70 other end of said lower rollers and paste and distributing rollers; and gears 36 on said short shafts and idlers 37 meshing therebetween are provided whereby said lower rollers, paste rollers and belt, are driven in one direction and the distributing 75 roller in the opposite direction, thereby effecting to transfer paste from the paste roller 19 and distribute it on the belt.

Stub shafts 40 (Figs. 1 and 2) projecting 80 from both ends of the upper roller 22 carry a feed-actuating crank 41, and a wiper-operating crank 42 respectively, 180 degrees apart. A feed shaft 45 (Fig. 2) mounted between said rear brackets 15 is provided with a motive arm 46 linked by a link 47 to 85 said feed crank 41, and carries a forwardly projecting active arm 50 fast on said feed shaft and having a lateral pin 51 at its free end loosely received in a slot 52 provided at the upper end of a pendant link 54 provided with an intermediate collar 55 between which and said arm 50 a spring 56 is compressed.

A label magazine 58 provided for the 90 labels 59 comprises a supporting floor 60 (Fig. 1) having an upturned rear wall 61 (Fig. 4) and upturned side walls 62, the latter being provided with upwardly and inwardly disposed lugs 63. Pivot brackets 64 (Fig. 1) fast on the rear part of said 95 side walls are provided with perforations 65 at their upper ends, and at their lower ends with outwardly disposed pivots or a pivot shaft 66 pivoting in the rear part of said side frames 11. A cover plate 68 disposed under said lugs 63 and having at its rear corners lateral projections 69 engaging in said perforations, has its forward end 72 adapted to be disposed over the rear part 100 of said upper supporting roller 22 (Fig. 2) 105 and forward of the forward end of said floor, thereby to permit the lowest label to 110

contact the belt. Said forward end 72 is provided on its upper face with a lug 74 pivoted to the lower end of said pendant link 54, whereby when the arm 50 is rocked 5 the magazine is moved downwardly and the lowest label yieldingly pressed by the spring 56, into contact with the belt. A feed and guide roller 76 disposed just above, and if desired, slightly spaced from, said upper 10 supporting roller 22 moves one of the labels from the magazine against the belt as the belt moves in the direction of the arrow, and the label therefor is then moved by the rollers 76 and 22 toward the front of the 15 machine.

A trough-shaped shelf 78 (Figs. 2 and 3) is mounted between said side frames just forward of said belt and is adapted to support a can, bottle or other article 79, to be labeled, 20 with its upper face just below the upper face of the upper roller, thereby to receive the labels fed from the rollers 76 and 22.

A bar 83 (Fig. 3) between the upper ends of said intermediate brackets 14 carries a 25 vertical square tubular guide bracket 84 midway on said bar and provided with a slot 85 (Fig. 2) in one side. A plunger 86 in said guide bracket is provided with a lateral stop 87 on its upper end, a notch 88 in the 30 rear part of its lower end, and a lateral pin 90 at its intermediate part and adapted to engage in said slot 85. A spring detent 92 mounted on the guide bracket is provided with a detent portion 93 (Fig. 1) adapted to 35 engage in said notch 88 and hold the plunger raised at its upper limit to give time for the label to be fed to the can or article 79.

A wiper-actuating shaft 95 is mounted on said forward bearing 13 and is provided 40 with a motive arm 96 linked by a link 97 to said wiper crank 42 and carries a rocking bracket 98 fast on said wiper shaft and having a lower lifting arm 99 and an upper depressing arm 100. A plunger actuating lever 45 103 is pivoted on said lifting arm 99 and adapted to be raised by the lifting arm and provided with an end slot 104 receiving said lateral pin 90 thereby to lift the plunger.

An adjusting screw 105 in said depressing 50 arm is adapted to adjustably engage and depress said plunger actuating lever 103 and to permit lost motion by said lever between said screw and arm 99. A tripping lever 108 fast on said wiper shaft is adapted at its 55 free end to engage said detent portion 93 thereby to release the plunger after the label has been applied to the can 79 or the like.

A pair of springs 110, the tendency of 60 which is to draw together or compress, is secured to the plunger 86, a spring on each opposite lateral face of the lower end of the plunger, each spring carrying one of the downwardly divergent arms 111.

Longitudinally disposed wiper rollers 112 65 are rotatably mounted between the lower

ends of said arms, and are adapted to engage the sides of the can 79, or the like, through the inwardly pressing action of the springs 110.

Plates 115 having curved under portions 70 116, are secured to the frame of the machine substantially on the plane of the line of the paste belt 25 in its engagement between the rollers 22 and 76, the upper horizontal surface of each plate 115 providing a shelf on 75 either side of the machine. The plate 115 adjacent to the paste belt 25 is provided with an edge 117 for stripping the labels from the paste belt at the roller 22. There is an opening or space 118 between the plates 80 115, Fig. 3, each label being moved by the rollers 22 and 76 onto the shelf formed by the plate 115 adjacent to these rollers and stretching across the opening 118 onto the shelf formed by the opposite plate 115. 85 The arms 111 being in raised position and drawn together by the springs 110, and the arms being moved downwardly by the plunger 86, the rollers 112 are moved downwardly and are brought into contact with the mid portion of the extended label and push the label downwardly through the opening 118, the respective ends of the label being guided by the respective rounded portions 116 of the plates or shelves 115. As the 90 rollers move farther downwardly they bring the label into contact with the can 79, or the like, and themselves then coming into contact with the rounded surface of the can, or the like, are thereby spread apart and over 95 the label and against the tendency of the springs 110 to draw them together, and roll over the rounding surface of the can, or the like, thus pressing or wrapping the label, which intervenes between the rollers and the can, over the surface of the can, or the like. The can 79, or the like, is removable manually after being labeled, the rollers 112 being moved to upward position and being drawn together for passage through the opening 100 118 by the tendency of the springs 110 secured to the arms 111.

The operation of the machine is very simple. A suitable adhesive is placed in the container 18; the labels to be applied are 105 placed outer-face up, in the magazine 58; and a can 79 or the like is placed in the trough of the shelf 78 (Figs. 2 and 3). The parts being in the position of Fig. 1, the crank handle 32 (Fig. 2) is revolved in the 110 direction of the arrow, thus moving the belt, and the various rollers in the direction of the arrows (Fig. 1) and causing the magazine to descend to the position of Fig. 2, whereupon the spring 56 presses the lowest 115 label upon the belt and causes it to be drawn between the rollers 76 and 28, receiving paste from the belt and being then deposited on the shelves formed by the plates 115 and extending across the opening 118. 120 125 130

While the above action was taking place the plunger was held raised by the detent portion 93 and the tripping lever 108 was being lowered. The tripping lever 108 engages and pushes the detent portion 93 from the notch 28, and the screw 105 forces down the actuating lever 103 and with it the plunger and the pressing rollers 112. The rollers 112 engage and press the label through 10 the opening 118 and onto the can or the like and move down to the position of Fig. 3, thus completing the pressing of the label onto the can. The labels do not tend to stick to the paste belt 25 because of the quality of the 15 paste customarily used, which does not become sufficiently adhesive until lapse of a period of time for drying after leaving the paste container 18, or until about the time the labels are pressed on the cans and the 20 like by the rollers 112.

Continued turning of the crank handle causes the parts to resume the positions of Fig. 1; whereupon the article 79 is removed and a new article to be labeled is substituted, and the operation is repeated as often 25 as desired.

I claim:

1. In combination, paste applying means; means for containing labels; means for feeding labels singly from the containing means to the paste applying means; and means for receiving the label after application of paste thereto by the paste applying means having an opening for passage of the label therethrough; the label being moved by the paste applying means from the label feeding means to said receiving means; means for supporting an article in position in the apparatus for pasting the label thereon; means for removing the label from said label receiving means through said opening and applying the label to said article; and means for moving the label-removing and applying means.

2. In combination, paste applying means; means for moving the paste applying means; means for containing labels; means for feeding labels singly from the containing means to the paste applying means; means for receiving the label after application of paste thereto by the paste applying means having an opening for passage of the label therethrough; the label being moved by the paste applying means from the label feeding means to said receiving means; means for supporting an article in position in the apparatus for pasting the label thereon; means for removing the label from said label receiving means through said opening and applying the label to said article; means for moving the label removing and applying means; and means for guiding the label removing and applying means in its movement.

3. In combination, paste applying means;

means for moving the paste applying means; means for containing labels; means for feeding labels singly from the containing means to the paste applying means; means for receiving the label after application of paste thereto by the paste applying means having an opening for passage of the label therethrough, the label being moved by the paste applying means from the label feeding means to said receiving means; means for supporting an article in position in the apparatus for pasting the label thereon; means for removing the label from said label receiving means through said opening and applying the label to said article; means for moving the label removing and applying means; and means appurtenant to said label receiving means for guiding the label through said opening.

4. In combination, paste applying means; means for moving the paste applying means; means for containing labels; means for feeding the labels singly from the containing means to the paste applying means; oppositely disposed means for receiving the label after application of paste thereto by the paste applying means; there being an opening between the oppositely disposed receiving means, said label engaging said oppositely disposed means and extending across said opening; the label being moved by the paste applying means from the label feeding means to said receiving means; means for supporting an article in position in the apparatus for pasting the label thereon; reciprocating means for removing the label from said label receiving means through said opening and applying the label to said article; and means for moving the reciprocating means.

5. In combination, paste applying means; means for moving the paste applying means; means for containing labels; means for feeding the labels singly from the containing means to the paste applying means; oppositely disposed means for receiving the label after application of paste thereto by the paste applying means; there being an opening between the oppositely disposed receiving means, said label engaging said oppositely disposed means and extending across said opening; said label being moved by the paste applying means from the label feeding means to said receiving means; means for supporting an article in position in the apparatus for pasting the label thereon; reciprocating means for removing the label from said label receiving means through said opening and applying the label to said article; means for moving the reciprocating means; and means for guiding the reciprocating means in its movement.

6. In combination, paste applying means; means for moving the paste applying means; means for containing labels; means for feed-

ing labels singly from the containing means to the paste applying means; oppositely disposed means for receiving the label after application of paste thereto by the paste applying means; there being an opening between the oppositely disposed receiving means, said label engaging said oppositely disposed means and extending across said opening; said label being moved by the paste applying means from the label feeding means to said receiving means; means for supporting an article in position in the apparatus for pasting the label thereon; reciprocating means for removing the label from said label receiving means through said opening and applying the label to said article; means for moving the reciprocating means; and means appurtenant to said oppositely disposed receiving means for guiding the label through said opening.

7. In combination, paste applying means; means for moving the paste applying means; means for containing labels; means for feeding the labels singly from the containing means to the paste applying means; oppositely disposed means for receiving the label after application of paste thereto by the paste applying means; there being an opening between the oppositely disposed receiving means, said label engaging said oppositely disposed means and extending across said opening; said label being moved by the paste applying means from the label feeding means to said receiving means; means for supporting an article in position in the apparatus for pasting the label thereon; reciprocating means for removing the label from said label receiving means through said opening and applying the label to said article; means for moving the reciprocating means; and means for guiding the reciprocating means in its movement; said reciprocating means comprising spring pressed arms provided with means for pressing the label upon the article to be labeled.

8. In combination, paste applying means; means for moving the paste applying means; means for containing labels; means for feeding the labels singly from the containing means to the paste applying means; oppositely disposed means for receiving the label after application of paste thereto by the paste applying means; there being an opening between the oppositely disposed receiving means, said label engaging said oppositely disposed means and extending across said opening; said label being moved by the paste applying means from the label feeding means to said receiving means; means for supporting an article in position in the apparatus for pasting the label thereon; reciprocating means for removing the label from said label receiving means through said opening and applying the label to said article; means for moving the reciprocating

means; and means for guiding the reciprocating means in its movement; said reciprocating means comprising spring pressed arms provided with means for pressing the label upon the article to be labeled; and said label receiving means comprising plates forming oppositely disposed shelves having an opening therebetween and each plate being provided with means for engaging a label for guiding it through said opening.

9. In combination, a paste applying belt; means for supporting said belt; means for moving said belt; a paste reservoir, means for applying paste to said belt from said reservoir; a label magazine; means for feeding the labels singly from the magazine to the paste applying belt, said belt moving the label after application of paste thereto by said belt; oppositely disposed shelves for receiving the label after application of paste thereto, there being an opening between the shelves, said label engaging the oppositely disposed shelves and extending across said opening; a trough for supporting an article in position in the apparatus for pasting the label thereon; reciprocating spring pressed arms movable through said opening for removing the label from said shelves through said opening and applying the label to said article; means for moving the reciprocating spring pressed arms; and means for guiding the spring pressed arms in reciprocatory movement.

10. In combination, a paste applying belt; means for supporting said belt; means for moving said belt; a paste reservoir; means for applying paste to said belt from said reservoir; a label magazine; means for feeding the labels singly from the magazine to the paste applying belt, said belt moving the label after application of paste thereto by said belt; oppositely disposed shelves for receiving the label after application of paste thereto, there being an opening between the shelves, said label engaging the oppositely disposed shelves and extending across said opening; a trough for supporting an article in position in the apparatus for pasting the label thereon; reciprocating spring pressed arms movable through said opening for removing the label from said shelves through said opening and having rollers for applying the label to said article; means for moving the reciprocating spring pressed arms; and means for guiding the label through said opening consisting of extended portions of said shelves.

11. In combination, a pair of side frames; a rotary supporting roller therebetween; a paste belt passing therearound; a pressing roller disposed just above said upper supporting roller for pressing the label against the belt; a feed shaft; means for oscillating said shaft as the roller is rotated; an arm fast on said feed shaft; a pendant link

- loosely connected to the end of said arm and having a collar; a spring compressed between said collar and arm; a label magazine comprising a floor having an upturned rear and side wall, and provided with upwardly and inwardly disposed intermediate lugs, upper rear perforations, and with rear lower pivots pivoting in the side frames; a cover plate pivoting in said perforations 10 and having its forward end forward of said floor and adapted to be disposed over the rear of said roller and pivoted to said link; means for supporting articles for receiving labels from said belt; and means for pressing labels on the articles.
12. In combination, a pair of side frames with a rear end bracket; upper and lower supporting rollers therebetween; a paste belt passing therearound; a stub shaft projecting from the upper roller; a feed-actuating crank on said stub-shaft; a feed shaft mounted between said brackets and provided with a motive arm linked to said feed crank; an active arm fast on said feed shaft and having a pin at its free end; a pendant link provided with a slot loosely receiving said pin; a label magazine pivoted at its rear end between said frames, and comprising a floor, rear and side walls, and a cover plate pivoted to the rear of said floor having its forward end forward of said floor and adapted to be disposed over said upper roller and pivoted to the pendant link; means for supporting articles for receiving labels from said belt; and means for pressing the labels on the articles.
13. In combination, a reciprocating device; arms yieldingly secured on said device; means for supporting an article for pressing a label thereon; pressing members mounted on said arms to press the label on said article; and oppositely disposed plates adapted to support the label in position above said article and to guide the label in downward movement against said article.
14. In combination, a pair of side frames; a roller between said frames; a paste applying belt disposed over said roller; means for moving said belt; a label magazine; means for feeding labels from said magazine to said belt for pasting the labels, the labels being moved by said belt after application of paste thereto; a trough forward of said roller to support the articles in position in the apparatus for labeling; a vertical tubular guide bracket supported between said frames; a plunger in said bracket; means for reciprocating the plunger; a pair of convergent springs on the lower end of the plunger; downwardly divergent arms secured on said springs; longitudinal wiper rollers mounted between the lower ends of said arms; and oppositely disposed plates secured on said frames providing an opening for passage of the labels
- therethrough and having portions adapted to engage the labels guiding the same.
15. In combination, in a labeling machine of the character described, a paste applying belt having sprocket chains attached thereto; and sprocket means for engaging said chains for moving the belt.
16. In combination, in a labeling machine of the character described, a paste applying belt having sprocket chains sewed to the edge of the belt; and sprocket means for engaging said chains for moving the belt.
17. In combination, in a labeling machine of the character described, a paste applying belt; a source of paste supply; sprocket means for moving said belt; and means for supplying paste to said belt from said source of supply.
18. In combination, a support for articles on to which sheets are fed; a plunger; a wiper actuating member having a lost motion connection for raising the plunger when a sheet is fed; means adapted to detain the plunger until the sheet is fed; means for releasing the plunger; and means on the plunger for pressing the sheets on the articles.
19. In combination, a movable paste applying means; a device reciprocated to feed sheets to said means; a support for articles for receiving labels from said means; a plunger over said support; a detent to hold the plunger raised; a reciprocatory wiper-actuating member; a member mounted for limited movement on said actuating member and loosely connected to said plunger for raising the plunger when said device feeds; a means adapted to engage said detent to release the plunger after the label is fed; and means on the plunger for pressing sheets on the articles.
20. In combination, a roller carrying a paste applying means; a device reciprocated by said roller to feed labels to said means; a shelf for supporting articles for receiving labels from said means; a vertical guide bracket supported over said shelf; a plunger in said bracket; a detent to hold the plunger raised; a wiper-actuating shaft; a bracket fast on said shaft; a lever pivoted for adjustably limited movement on said bracket and loosely connected to said plunger; a wiper-operating crank on said roller operatively connected to said shaft to raise the plunger when said device feeds; a tripping lever fast on said shaft and adapted to engage said detent to release the plunger after the label is fed; and means on the plunger for pressing labels on the articles.
21. In combination, a paste applying belt; a magazine adapted to reciprocate to feed labels to said belt; a shelf for supporting articles to receive labels from said belt; a vertical tubular guide bracket above said

- shelf; a plunger in said bracket and provided with a notch; a spring detent on the bracket engaging in said notch to hold the plunger raised while a label is fed; a roller 5 for moving said belt; a feed actuating crank at one end of said roller and adapted to operate the magazine; a wiper-operating crank on the other end at an angle of 180° to the feed crank; a wiper-actuating shaft 10 provided with a motive arm linked to said wiper crank; a rocking-bracket fast on said wiper shaft and having a lower lifting arm and an upper depressing arm, the latter carrying an adjusting screw; a plunger 15 actuating lever pivoted between said arms and loosely connected to said plunger and adapted to be depressed by said screw and to be raised by the lifting arm to permit motion by said lever between said screw 20 and arm; a tripping lever fast on said wiper shaft and adapted to engage said detent thereby to release the plunger after the label is fed; and means on the plunger for pressing labels on the articles.
- 25 22. In combination, a paste applying means; a device adapted to feed labels to said means; a shelf for supporting articles for receiving labels from said means; a vertical tubular guide bracket supported above 30 said shelf and provided with a lateral slot; a plunger in said bracket and provided with a notch, and a lateral pin engaging in said slot; a spring detent to hold the plunger raised; an oscillatory wiper-actuating 35 shaft; a lifting arm a plunger actuating lever pivoted for limited movement on the lifting arm and having a slot loosely receiving said lateral pin; a tripping lever fast on said shaft and adapted to engage said 40 detent thereby to release the plunger; and means on the plunger for pressing labels on the articles.
23. In combination, a support; a belt 45 passing over said support; chains secured to the belt; means engaging said chains to
- move the belt; a device to feed sheets to said belt; and means for receiving sheets from said belt and operating upon them.
24. In combination, supporting rollers; a paste belt passing over said rollers; 50 sprocket wheels at the ends of the rollers; sprocket chains secured to the edge of said belt and engaging around said sprocket wheels; a device to feed labels to said belt; a shelf for supporting articles for receiving 55 labels therefrom; and means for pressing the labels on the articles.
25. In combination, side frames; an upper and lower supporting roller therebetween; a paste belt passing over said rollers; 60 means for applying paste to the belt; sprocket wheels at the ends of the supporting rollers; sprocket chains sewed to the edge of said belt and engaging around said sprocket wheels; a magazine to feed labels 65 to said belt in front of said upper roller; a shelf for supporting articles just forward of said belt for receiving labels therefrom; and means for pressing the labels on the 70 articles.
26. In combination, a base; a pair of side frames thereon; a paste container on said base between the lower part of said frames; a paste roller transverse to said frames and dipping in said container; a distributing 75 roller resting upon said paste roller and upper supporting roller, and a pair of lower supporting rollers rotatable between said frames; a paste belt disposed around said supporting rollers over said upper roller 80 and under said lower rollers and engaging over said distributing rollers; a magazine to feed labels to said belt; a shelf for supporting articles just forward of said belt 85 for receiving labels therefrom; and means for pressing labels on the articles.

ADOLF POLLATSEK.
